UNITED STATES PATENT OFFICE.

ROBERT G. CLARK, OF BROOKLYN, NEW YORK.

BOAT SUPPORTING AND LAUNCHING APPARATUS FOR SHIPS.

1,344,754.

Specification of Letters Patent. Patented June 29, 1920.

Application filed September 13, 1917. Serial No. 191,103.

To all whom it may concern:

Be it known that I, ROBERT G. CLARK, a citizen of the United States, and a resident of the borough of Brooklyn, in the county 5 of Kings, city and State of New York, have invented certain new and useful Improvements in Boat Supporting and Launching Apparatus for Ships, of which the following is a specification.

10 This invention relates to apparatus for supporting life boats, rafts and the like upon the deck of ships and to launch the same from the ship, and it is the primary object of the invention to provide apparatus 15 of this character which is simple, cheap and novel in construction and efficient in operation.

It is a further object of the invention to provide apparatus of this character in which 20 the entire supporting and launching apparatus is carried by the ship and entirely free of the boat to be launched, the apparatus being automatically operative by the gravity of the boat load and set in operation and 25 the lowering of the boat controlled and regulated by a person in the boat being launched.

Other objects and advantages will herein-after appear.

In the drawings accompanying and forming 30 a part of this specification Figure 1 is an end elevation of an embodiment of my invention applied as a boat launching and supporting apparatus and showing the same in normal boat supporting position.

35 Fig. 2 is a view similar to Fig. 1 but showing the same in boat launching position.

Fig. 3 is a side elevation looking at the right of Fig. 1; and

40 Fig. 4 is a detail of the means to control the boat launching and lowering apparatus, showing the same in full lines in normal locked position and in dotted lines in released position, said figure also showing 45 braking means to regulate the boat lowering means from the boat.

Similar characters of reference designate like parts throughout the different views of the drawings.

50 The embodiment of my invention shown in the drawings comprises a pair of standards 6 fixed as to the deck of a ship, shown

in a general way at S, these standards being so spaced and located as to be adjacent opposite ends of a boat B to be supported and launched by the apparatus, as shown in Fig. 3. A davit or lever 7 is pivotally supported to swing on a horizontal axis by each of said standards, as at 8, said davits being adapted to extend in an upright position as shown 60 in Figs. 1 and 3, and to be moved to a position where they extend laterally from the side of the ship, as shown in Fig. 2. The davits have a part 9 to conform substantially to and engage a side and a bottom portion 65 of the boat B to be supported in the upright position of the davits, and has blocks 10 of suitable material, such as wood or the like, to serve as a filler and cushioning means between the davits and the boat. Arms 11 70 fixed to a shaft 12 rotatably supported by the standards 6 have a portion 13 conforming substantially to and engaging a portion of the bottom of the boat and the side opposite to the portions 9 of the davits, as clearly 75 shown in Fig. 1, said arms also having filler cushioning blocks 14.

The davits are moved to and retained in upright position and permitted to move to boat launching position by a winch or windlass mechanism, comprising a drum 16 journaled in standards 17, 17 secured to the deck of the ship S, said drum being rotatable to move the davits to boat supporting position by a crank 18 secured to a wheel 19 fixed to a 80 shaft 20 journaled in the standards 17, a pinion 21 fixed to said shaft meshing with a gear 22 fixed to a shaft 23, and a pinion 24 on said latter shaft meshing with a gear 25 rotatable with the drum 16. Cables or 85 ropes 27, 27 are connected to said drum in such manner that as the drum is rotated in one direction both cables are wound upon the drum, and as the drum is rotated in reverse direction the cables are unwound. The 90 cables pass under pulleys or sheaves 28, 28 and over pulleys 29, 29 rotatably carried adjacent the lower and upper ends of the davit-supporting standards 6 and over pulleys 30 carried at the free ends of the davits 95 and maintained in engagement with said latter sheaves 30 by wheels 31 carried at the extended ends of the davits, with the ends 100 of the cables connected to bars 32, 32 hav-

ing a hooked end 33 to releasably connect the same with eye bolts 34 or the like secured to the boat B.

In the operation of moving the boat B to position with the davits and arms 11 engaging at opposite sides of the boat, or from the position shown in Fig. 2 to that shown in Fig. 1, the drum 16 is rotated through the crank 18 to wind the cables 27 thereon. During such rotating of the drum the boat B is raised until the bars 32 assume the position shown in Fig. 2 when the davits 7 by the continued winding of the cables on the drum will be moved to the upright position shown in Fig. 1. During the upward movement of the davits projections or horns 36 on the davits will engage in openings 37 in the bars 32 for a purpose to be herein-after described. The davits are maintained in upright position by the cables 27 through a pawl 38 caused by a spring 39 to engage with a ratchet wheel 40 rotatable with the shaft 20.

During the upward movement of the davits and as they approach their upright position rollers 42 carried by extensions of the arms 11 are engaged by the davits, thereby lifting the arms 11 and moving them to assume a position at the bottom portion and side of the boat opposite to the portions 9 of the davits, the davits retaining the arms in such position. Simultaneously with this movement of the arms 11 an angle bar 43 fixed to and extending between the arms 11 and fixed to arms 44 fixed to the shaft 12, to extend longitudinally of the boat B, engages with and supports the boat at the keel, as clearly shown in Figs. 1 and 3.

The davits 7 are supported in boat launching position shown in Fig. 2 by arms 53 pivotally supported by the standards 6 and slidably engaged between pins 54 extending laterally from the davits, a hook 55 formed at the free end of each arm latching over the lower pins 54 and maintained in latched position by the upper pins. After the boat has been raised to the position shown in Fig. 2 with the horns 36 about to engage in the openings in the bars 32 the cables 27 will have no further movement over the davit sheaves 30 with the result that by the continued winding of the cables on the drum 16 the davits will be moved to upright position, this movement of the davits automatically unlatching the arms 53 and, by the engagement of the arms between the davit pins 54, lifting said arms until the boat is moved to the position with the angle bar 43 in engagement with and supporting the boat, when the davit pins 54 will engage with opposite beveled or cam portions 67 of the arms 53 forcing said arms down onto the boat B and thereby rigidly clamping the boat to the supporting bar 43. It will be obvious that as the davits are moved from

the Fig. 2 to the Fig. 1 position the direction of force upon the davits will deviate or change, with the result that when the stress is upon the davit sheaves and the line or direction of force at one side of the pivotal support of the davits there will be an impulsive force imparted to the davits tending to suddenly move the davits upward toward the standards 6 and there will be a consequent dropping of the boat before the keel supporting member 43 has been moved to boat supporting position. To obviate this the davit horns 36 to engage in the bar openings 37 are provided. As the direction of force or stress changes during the upward movement of the davits and cause them to move suddenly the horns 36 will engage with the upper wall of the bar openings 37 and thereby hold the davits against such movement.

In order that a person in the boat may release the pawl 38 from the ratchet wheel 40 to set the apparatus in operation to launch the boat there is provided a light cable or rope 45 wound on a drum 46 having a hand wheel 47, said drum being rotatably carried by one of the bars 32. The cable leads from the drum over a sheave 48 rotatably mounted on a stud extending laterally from one of the davits 7, over a sheave 49 rotatably mounted on a stud projecting from a standard 6 and under sheaves 50 and 51 with the free end connected to the pawl 38.

As the pawl 38 is thus released from the ratchet wheel 40, the point of suspension of the load from the davits will be at one side of the pivotal support of the davits toward the out port side of the ship, the weight of the boat resting upon the keel supporting bar 43 will move the arms 11 downward to boat-releasing position, the arm-rollers 42 pulling the davits laterally to start the davits to move downward to boat launching position, thereby unwinding the cables 27 from the winch drum 16 and permitting the davits to move to boat launching position, this movement of the davits releasing and lifting the arms 53 from the top of the boat B. During this movement of the davits there will be no boat lowering movement imparted to the boat by the cables over the davit sheaves due to the engagement of the davit horns in the openings in the bars 32. It will be obvious that also during the lowering movement of the davits, or from the Fig. 1 to the Fig. 2 position, the direction of force or stress upon the davits will deviate to one side of the pivotal support of the davits tending to impart an impulsive or sudden movement to the davits with the resultant dropping of the boat. This movement of the davits due to the change in the direction of force or stress thereon is obviated by the engagement of 130

the horns 36 in the bar openings 37, said horns moving to position to engage the lower wall of such openings and be lowered as the cables are paid out by the drum 16 5 until they are arrested and supported by the hooked ends of the arms 53. In this position the horns 36 will be withdrawn from the bar openings and the boat lowered by the cables 27.

10 As the davits move to boat launching position and the boat is lowered the cable 45 will be unwound from the drum 46 and revolve the drum. To regulate and control, or stop, the lowering movement of the boat 15 brake mechanism is provided which is operable from the boat, and comprises a brake shoe 56 carried by the pawl 38 which is adapted to frictionally coöperate with the hand wheel 19 to retard the movement of the 20 winch mechanism. Should it be desired to retard the lowering movement of the boat, or stop such movement, the hand wheel 47 of the drum 46 is grasped by a person in the boat thereby preventing the rotating of the 25 drum and the consequent unwinding of the cable therefrom and the drawing of the cable taut thereby causing the brake shoe 56 to forcibly engage the wheel 19. This braking mechanism is particularly adapted to 30 stop the lowering movement of the boat. However, the speed at which the davits and boat is lowered are controlled and governed automatically by braking means operable by a centrifugal governor actuated by the movements 35 of the winch mechanism, and comprises a friction clutch, shown in the drawings as of the cone type, one member 58 of which is fixed and the other member 59 slideable on and rotatable with the shaft 20. The 40 clutching movement of the clutch member 59 is controlled by weighted arms 60 pivotally mounted on and rotatable with the shaft 20 and through the action of centrifugal force are thrown laterally against the 45 action of springs connecting said arms, the same being in the nature of a centrifugal governor. The clutch member 59 is connected by links 61 to said arms and moved to clutching position as the weighted arms 50 are thrown laterally through the velocity of the rotation of the cable drum and thereby check or retard the speed of the drum. The hooked portion 33 of the bars 32 are beveled and as the boat is launched and the strain 55 on the bars relieved by the boat such hooked portions will be disengaged from the eye bolts 34 and free the bars and thereby the cables 27 from the boat.

To automatically release the launching 60 mechanism in the case of a sinking ship float controlled mechanism is provided to trip the pawl 38, comprising a float, which may consist of a tank 63, connected by a rod 64 to one arm of a pivoted angle lever trip 65 the 65 other arm of which is adapted to coöperate

with the pawl 38 to release the same from the ratchet wheel 40. As the float comes in contact with the surface of the water the buoyancy thereof upon the further sinking movement of the ship will move the rod 64 70 upward thereby causing the trip to engage with the pawl 38 and throw it out of engagement with the ratchet wheel 40.

Having thus described my invention, I claim:

1. In boat supporting and launching apparatus for ships, davits pivotally supported to extend in upright position and adapted to be moved to position to extend laterally from the ship; a support to support the boat at 80 the keel maintained in boat supporting position by the davits when in upright position and permitted to move to boat releasing position with the movement of the davits to extend laterally from the ship; means including a winch and cables to move the davits to upright position and to position to extend laterally from the ship to lower the boat; pawl and ratchet mechanism to lock the winch against movement and the davits 90 in upright position releasable from the boat to permit movement of the winch and thereby the davits to boat launching position; and centrifugal governor controlled means to regulate the movement of the winch and 95 thereby the lowering of the davits and boat, substantially as and for the purpose specified.

2. In boat supporting and launching apparatus for ships, davits pivotally supported to extend in upright position and adapted to be moved to position to extend laterally from the ship; a pair of arms carrying a bar to engage with and support the boat at 100 the keel and maintained in boat supporting position by the davits when in upright position and permitted to move to boat releasing position with the movement of the davits to position to extend laterally from the ship; means including a winch and a pair of 105 cables to move the davits to upright position and to position to extend laterally from the ship to lower the boat; pawl and ratchet mechanism to lock the winch against movement and the davits in upright position and operable from the boat to permit movement of the winch and thereby the davits to move to position to lower the boat; a friction clutch one member of which is fixed and the other member movable with 110 the winch; and a centrifugal governor operable by the winch to actuate the movable clutch member to coöperate with the fixed clutch member to retard the davit and boat lowering movements of the winch, substantially as and for the purpose specified.

3. In boat supporting and launching apparatus for ships, davits pivotally supported to extend in upright position and adapted to be moved to position to extend laterally 115

from the ship; a pivotally supported bar to engage and support the boat at the keel moved to and maintained in boat supporting position by the davits when moved to and 5 in upright position and permitted to move by gravity to boat releasing position with the movement of the davits to position to extend laterally from the ship; pivotally supported arms to extend over the boat and 10 operable by the davits when in upright position to clamp the boat to the keel support and released from the boat when the davits are moved to position to extend laterally from the ship, and said arms adapted to 15 support the davits in boat launching position; means including a winch and cables operable to move the davits to and retain them in upright position and to position to extend laterally from the ship and to lower 20 the boat; releasable means to maintain the winch inoperative and retain the davits in upright position and operable from the boat to release the winch to move the davits to boat lowering position; and braking means 25 controlled by a centrifugal governor actuated from the movements of the winch to control the boat lowering movements of the latter, substantially as and for the purpose specified.

30 4. In boat supporting and launching apparatus for ships, the combination of standards; davits pivotally carried by said standards, said davits being adapted to be retained in upright position and to move by 35 gravity to position to extend laterally from the ship to launch the boat; means operable by said davits when moved to upright position to engage and support the boat at the keel; an arm pivotally carried by each 40 standard to automatically engage a pin extending from the davits to support the latter in boat launching position; and said arms being movable by the davits when moved to upright position to engage over the boat 45 and caused by the davits to clamp the boat to the keel support; a winch; and cables to permit movement of the davits to boat launching position and to lower the boat, and to raise the boat and the davits to up- 50 right position and retain the davits in upright position and support the boat, substantially as and for the purpose specified.

5. Boat supporting and launching apparatus for ships, comprising a pair of standards; a pair of davits pivotally carried by the standards, said davits being adapted to be retained in upright position and to move by gravity to extend laterally from the ship to position to launch the boat; means con- 55 trolled by the davits when moved to upright position to support the boat at the keel and to release said means when the davits move to position to extend laterally from the ship; an arm pivotally carried by each standard 60 movable by the davits to engage over and

clamp the boat to the keel support when the davits are moved to upright position and released from boat clamping position by the davits when moved to position to extend laterally from the ship and to automatically 70 engage pins projecting from the davits to support the davits in boat launching position; a winch including a cable for each davit; and means to connect the boat to the cables and coöperate with the davits to control the movements of the davits, substantially as and for the purpose specified. 75

6. Boat supporting and launching apparatus for ships, comprising in combination a pair of standards to be fixed to the ship; 80 a davit pivotally supported by each of the standards; a winch; a pair of cables to move the davits to and retain them in upright position, said davits having means to engage one side and the bottom of a boat adjacent opposite ends when in upright position; an arm pivotally carried by each of the standards to hold the davits in boat launching position; an arm pivotally carried by each standard adapted to engage 85 at the side of the boat opposite to the davits; a support carried by said latter arms to support the boat at the keel; and a roller carried by each of said latter arms to engage the davits to move said arms with the support 90 carried thereby into boat supporting position as the davits are moved to upright position and permit said arms to move to boat releasing position with the movement of the davits as they are released by the winch 100 cables and move to boat launching position, substantially as and for the purpose specified.

7. In boat supporting and launching apparatus for ships, davits supported to be 105 moved to position to extend upright or laterally from the ship; a pivotally supported bar to engage and support the boat at the keel moved to and maintained in boat supporting position by the davits when the latter are moved to upright position, and said bar being adapted to move by gravity to boat releasing position with the movement of the davits to position to extend laterally from the ship; and pivotally supported 110 arms to extend over the boat and operable by the davits when in upright position to clamp the boat to the keel support, and released from the boat by the davits when the latter are moved to position to extend 115 laterally from the ship, and said arms adapted to support the davits in said latter position.

8. In boat supporting and launching apparatus for ships, davits supported to be 120 moved to position to extend upright or laterally from the ship; means to engage and support the boat at the keel moved to and maintained in boat supporting position by the davits when the latter are moved 125

to upright position, and said means being adapted to be released from the boat with the movement of the davits to position to extend laterally from the ship; and means 5 operable by the davits when in upright position to engage over and clamp the boat to the keel support, and released from the boat by the davits when the latter are

moved to position to extend laterally from the ship, and said means being adapted to 10 support the davits in said latter position.

Signed at the city of New York, in the county of New York, and State of New York, this 29th day of August, 1917.

ROBERT G. CLARK.
